UNITED STATES PATENT OFFICE.

OTTO A. SAUER, OF SAN ANTONIO, TEXAS, ASSIGNOR OF THREE-FOURTHS TO EUGENE D. NIMS, OF ST. LOUIS, MISSOURI.

FEED CONTROL FOR PULVERIZING MILLS.

Application filed August 16, 1923. Serial No. 657,796.

To all whom it may concern:

Be it known that I, OTTO A. SAUER, a citizen of the United States of America, and a resident of San Antonio, county of Bexar, 5 and State of Texas, have invented a new and useful Improvement in Feed Control for Pulverizing Mills, of which the following is a specification.

This invention relates to feed control 10 means for roller-mills wherein the pulverized product is removed from the mill by an air current.

The main objects of this invention are to 15 provide improved mechanism for controlling the feeding of raw material to the mill; to provide improved means actuated by the condition of the air current for regulating said feeding mechanism; and to provide improved related means and mechanism of this 20 kind whereby the feeding of raw material is automatically proportioned to the capacity of the mill to effect a satisfactory pulverization and removal of the material.

An illustrative embodiment of this invention is shown in the accompanying drawings, in which:

Figure 1 is a vertical, sectional elevation 30 of a special type of pulverizing roller-mill showing an improved feed control, constructed in accordance with this invention, applied thereto, the feed control being illustrated somewhat diagrammatically.

Figure 2 is a plan of the same.

Figure 3 is a detail view further illustrating the manner in which the feed control functions.

One common form of pulverizing mill heretofore in use requires the constant services of an attendant to control the feed of material into the mill so as to prevent choking at the crushing rollers. The present invention provides a roller mill which is entirely automatic in its operation so as not to require the services of an attendant after the material has been placed in the hopper to be fed to the rolls. The device includes improved automatic mechanism for controlling the feed of material from the hopper to the rolls. This improved mechanism is actuated by an air motor controlled by changes in the static pressure of the air current within the mill, depending upon the amount of material located at the rolls. In construction, the mill is somewhat similar to a Venturi tube in which the grinding chamber

forms the reducing cone and the separating chamber forms the expanding cone, with the rollers located at the throat of the Venturi tube. The material in process tends to obstruct the passage of the air through the throat, thereby controlling the static pressure in the grinding chamber. The static pressure in the grinding chamber is proportional to the amount of material obstructing the throat. If the mill is choked by an excess amount of material, the air pressure in the grinding chamber increases and the air motor is thereby actuated to close the inlet valve of the feed chute until a sufficient amount of material passes through 70 the rolls to materially reduce the air pressure within the grinding chamber.

In the specific embodiment herein illustrated, the improved feed control is shown as applied to a vertical pulverizing mill of 75 the "Raymond" type, but it is also applicable to other types and makes of mills.

The mill comprises a housing 1 which provides a grinding chamber 2 and an air separating chamber 3 arranged one above the other and communicating with each other. The raw material enters through the opening 4 where it is delivered to the grinder 5 and the pulverized finished product is carried by an air current up into the separator 3 and out through an outlet port 6 to a suitable collector c. An air inlet pipe 7 connects with an annular conduit 7^a surrounding the grinding chamber 2 and communicating with said conduit through ports 7^b for distributing the incoming air in the grinding chamber 2.

The grinder 5 as herein shown, comprises a plurality of rollers 8 secured to shafts 9 which are journaled in casings 10 pivotally suspended on a carriage 11 mounted on a shaft 12 journaled in a central bearing 13. This pendulous mounting of the rollers 8 causes them to swing outwardly during the rotation of the member 11 so as to bear against a bull-ring 14 arranged on the adjacent inner wall of the housing 1. Rigidly mounted on the carriage 11 is a plurality of blades or plows 15 located in advance of each roller 8 and arranged to revolve with the carriage 11 and to lift the raw material in the grinding chamber to a plane where it is caught between the rollers 8 and bull-ring 14.

Suitable air pumping means such as a 110

blower B connects with the air inlet pipe 7 so as to set up an air current through the grinding and separating chambers for the purpose of forcing the pulverized product 5 through the grinder 5 and discharging it into the collector C from which collector the finished product is delivered to suitable containers. It is desirable to connect the air outlet of the collector to the blower B 10 so that any of the dust escaping from the collector is carried back to the mill and again delivered to the collector.

The specific embodiment of the feed control herein shown comprises a chute 16 15 through which a flow of material is controlled by a pair of gates 17 and 18 operated respectively by an eccentric and crank mechanism 19 and a motor device 20.

The chute 16 is suitably arranged with 20 respect to the mill and has its lower end connected to the material inlet 4 and its upper end connected to a bin or other suitable source of supply. Inasmuch as there is an air current through the mill the chute is 25 substantially air tight up to the gate 18.

Above that the chute may be partially open on the top side if desired.

The gate 17 is slidably mounted transversely of the chute in suitable guideways 30 arranged for that purpose. The gate 18 is similarly mounted in the chute between the gate 17 and the material inlet 4 of the mill.

The eccentric and crank mechanism 19 35 for operating the gate 17 includes an eccentric 21 journaled on a shaft 22 and having a rod 23 connecting it with an arm 24 which is attached to a shaft 25 journaled on chute 16 and connected to the gate 17 by an arm 40 26. The connection of the rod 23 and arm 24 is made adjustable so as to vary the action of the eccentric-crank mechanism 19 on the gate. During the operation of the mill, the gate 17 is reciprocated continuously 45 so as to serve as an agitator thereby facilitating the flow of material through the chute.

The motor device 20 is a suitable form of bellows of diaphragm construction arranged 50 on the side of the housing 1 adjacent to the grinding chamber 2 so as to communicate with the annular air conduit 7^A. A rod 27 and a rod 28, connected together by a bell-crank lever 29, communicate the movements 55 of the diaphragm motor device 20 to the gate 18 through the medium of a lever 30 mounted on the chute 16. A turnbuckle 31 may be arranged on rod 28 for the purpose of properly adjusting the gate 18 to the 60 action of the motor device 20.

The driving mechanism for the mill and the feed control comprises a driving shaft 32 which is connected to the shaft 12 by gear and pinion 33 and to the shaft 22 by 65 a suitable belt and pulley connection 34. A

pulley 35 is arranged on shaft 32 for connection with a source of power.

The mill, and the feed control therefor, as herein shown and described operate substantially in the following manner:

As the carriage 11 is rotated the rollers swing out against and revolve around the bull-ring 14. The plows 15 throw the material up between the rollers 8 and the bull-ring 14 where it is pulverized by the grinding action of the rollers and bull-ring. The air current produced by the blower B forces such of the fine material as is not too heavy up into the separating chamber 3 and out through the port 6 and delivers it to the collector C. The material that is too heavy to be removed by the air current falls back in the grinding chamber 2 and is re-ground.

As the mill operates the eccentric 21, acting through the rod 23 and arm 24, shaft 25 and arm 26, reciprocates the gate 17, causing it to be intermittently opened and closed for releasing and checking the flow of raw material through the chute 16 toward the gate 18.

The gate 18 is normally arranged so as to be raised from the bottom of the chute a predetermined distance such as will allow for a predetermined quantity of raw material to pass to the material opening 4. If for any reason an excessive amount of the pulverized material in the grinder 5 and in the separating chamber 3 tends to retard the free movement of the air current and dust therethrough, there is a building up of pressure in the grinding chamber 2 and in the annular conduit 7^A. This increased pressure reacts on the diaphragm motor device 20 so as to cause it to shift the gate 18 to reduce the size of the opening between it and the chute, thus decreasing the supply of raw material fed to the mill. As soon as the accumulation of pulverized material in the mill is eliminated and a normal flow of air current is re-established the diaphragm motor 20 reacts so as to produce a further opening of the gate 18 and an increase of the supply of raw material to the mill.

It will thus be seen that through the medium of the motor device 20 and its mechanical connections to the gate 18 the supply of raw material is automatically proportioned to the capacity of the mill to pulverize the same and have the pulverized product removed by the air current. Such a feed control results in a more steady and uniform operation of a mill and a more uniform and abundant yield of the finished product.

Although but one specific embodiment of this invention has been herein shown and described, it will be understood that certain details of the construction shown may be altered or omitted without departing from

the spirit of this invention as defined by the following claims.

I claim:

1. In a pulverizing machine, grinding means, a feed control, comprising a chute, a pair of gates arranged to control the flow of material along said chute, mechanism connected to be actuated by the means for constantly reciprocating one of said gates for intermittently checking and releasing the flow of material along said chute, a motor device connected with the machine and adapted to be actuated by changes created therein by variations in the volume of the finished product, and a mechanical connection between said motor device and the other gate, whereby said other gate is shifted by said motor device for regulating the quantity of material delivered to the machine.
2. In a pulverizing machine wherein the pulverized material is removed by an air current, grinding means, a feed control comprising a chute, a pair of gates arranged to control the flow of material along said chute, mechanism connected to the foremost gate and adapted to be actuated by said means for constantly reciprocating said gate to intermittently check and release the flow

of material along said chute, and a diaphragm motor device connected with said machine and adapted to be actuated by changes in the air current created by variations in the volume of finished product, said motor device being connected to the other gate, whereby said other gate is shifted by said motor device for regulating the quantity of material delivered to the machine.

3. A pulverizing mill comprising a grinding chamber, an air separating chamber above said grinding chamber and communicating therewith through a restricted throat, grinding means located in said throat, air circulating means for normally forcing a current of air upwardly through said chambers, means controlling the feed of material to said chambers, and an air motor communicating with said grinding chamber below said throat and adapted to be actuated by an increase of air pressure in said grinding chamber through the choking of said throat by an excess amount of material, said air motor being arranged to actuate said feed control means for reducing the feed of material when said throat is choked.

Signed at San Antonio this 9th day of August, 1923.

OTTO A. SAUER.
